Fig. 3.

UNITED STATES PATENT OFFICE

CLAUDE L. POST, OF CHICAGO, ILLINOIS

SHEET FEEDING MECHANISM

Application filed August 29, 1928. Serial No. 302,832.

My invention relates to sheet feeding mechanism and has among its objects the production of mechanism of the kind described, which is convenient, durable, efficient and satisfactory for use wherever found applicable.

My invention relates to the same general type of feeding devices as that forming the subject matter of my copending application, Serial No. 92631, filed March 5, 1926.

A particular object of the invention is to provide improved mechanism for feeding sheets of paper, envelopes, or the equivalent, to printing devices, embossing machines, folding machines, etc.

Another particular object of the invention is to provide improved mechanism adapted to feed sheets of various thicknesses without adjustment therefor.

Still another particular object of the invention is to provide improved sheet feeding mechanism adapted to feed relatively thin stock without injury thereto.

A particular object of the present invention is to provide means whereby the feed of envelopes or the like may be so regulated that they will not pile up and jam the feeding mechanism, but will be delivered in a steady and frequent stream.

A further object is to provide such a device in which the supply of stock from a reservoir is automatically controlled by the stock being fed.

A still further object is to provide such a device in which the feeding mechanism is so controlled that the feeding devices are brought gently into contact with the stock, avoiding injury thereto.

A still further object is to provide feed control mechanism which is adjustable according to the width of the stock to be fed.

Many other objects and advantages of the construction herein shown and described will be obvious to those skilled in the art from the disclosure herein given.

To this end my invention consists in the novel construction, arrangement and combination of parts herein shown and described, and more particularly pointed out in the claims.

Referring now to the drawings forming part of the specification:

Fig. 1 is a plan view of a device embodying my invention;

Fig. 2 is a fragmentary side elevation of 55 the device shown in Fig. 1;

Fig. 3 is a sectional view taken on line 3—3 of Fig. 1; and

Fig. 4 is a fragmentary detail elevation of a portion of a device embodying my invention. 60

A preferred embodiment of my invention is shown in the drawings, wherein the reference character 20 designates generally a frame for the improved feeding mechanism, adapted to feed envelopes, sheets of paper, or the like to a printing machine, embossing machine, wrapping machine, folding machine, or any other type of machine adapted to use sheets or envelopes.

In the present instance, the printing machine is indicated generally at 22 and will not further be described, inasmuch as it may be of any suitable type.

A sprocket chain 23 carried by a sprocket 24 mounted on a shaft 25 transmits motion from the printing machine to the feeding device. Any suitable means (not shown) is provided for driving the shaft 25, which may carry a pinion 26. Suitable feed rolls (best seen in Fig. 3 and described below) are provided for advancing the stock to the printing device.

The pinion 26 meshes with a train of pinions 27 and 28 which transmit the motion from the shaft 25 to a shaft 29 on which is 85 mounted feed wheels or rolls 31. Parallel to the shaft 29 is a shaft 32, these two shafts being connected by means of a sprocket chain 33. The shaft 32 also carries feed wheels or rolls 35. Feed rolls 36 and 37 are mounted on suitable stud shafts and engage the rolls 31 and 35 to advance the sheets or other articles to a conveyor 37, a roller 38 engaging the sheets as they are fed into the conveyor. Pinned to the shaft 25 are sprockets 47 meshing with sprocket chains 48, which chains also mesh with sprockets 49 rotatably journaled upon a stationary bearing 50, mounted in the frame 20, this bearing rotatably carrying collars (not shown) for positioning the sprock- 90 95

ets. Interposed between the sprocket chains 48 and arranged to travel therewith are pins 53 which carry feeding devices, which feeding devices comprise bent bars 55 having hubs 56 rotatably journaled upon one of the pins 53. Interposed between each pair of bent bars are disks 59 rotatably journaled upon a pin 60 mounted in the bars, and secured to the bars at their free ends is a friction member 64 formed of any suitable material having a high coefficient of friction and mounted in a suitable housing member 63. I preferably form the friction members 64 from sponge rubber or the equivalent and they are retained in the housing member 63 by frictional engagement therewith.

As will be clearly seen in Fig. 2, the bearing 50 is adjustably secured by means of a set screw 90 in the frame 20 in order that the tension on the sprocket chain 48 may be adjusted as desired. Integral with the frame 20 is a pair of arms 91 carrying a cross bar 89 (Fig. 1) which supports an arcuate guard member 92. Pivoted to this arcuate member 92 at 93, and forming a continuation thereof, is an arcuate member 94 having a counterpoise 95 slidably mounted on a rod 96. Dogs 97 on the member 94 limit the upward displacement thereof when the member 94 is elevated by the counterpoise 95 or by other means. It will be readily apparent that the lower edge of the member 94 is normally disposed slightly above the table 69.

A crank 101 is adjustably secured to the shaft 25 by a set screw 101' and has pivotally secured thereto a pitman 102, pivoted to which is a lever 103. The lever 103 is pivotally secured to the frame 20 by means of a shaft 105. A pawl 106 is pivotally mounted on the lever 103 and has a tooth 108 adapted to engage a ratchet wheel 109 rigidly secured to the shaft 105. Carried by the shaft 105 and by a shaft 107 is a conveyor 107', which serves to advance articles from a table or magazine to the feeding device.

As will be clearly seen in Figs. 2 and 4, the pawl 106 is normally retained by means of a leaf spring 110, this spring being adjustably secured to a projecting portion 111 of the lever 103 and oscillating therewith. The leaf spring 110 has a bent portion 113 adjacent one end which is adapted to engage a notch 114 in the pawl. Mounted on a stud shaft 116 integral with the pawl 106 (best seen in Fig. 1) is a roller 117 and projecting from the opposite side of the pawl is a lug 119. A cam 120 is secured to the frame 20 in the path of the roller 117.

A shaft 122 extends transversely of the frame 20 and has adjustably secured thereto by means of a set screw 123, a crank 124 disposed in the path of one of the disks 59, although shown in Fig. 1 in the path of the center disk. This crank may be adjusted toward the right (Fig. 3) for feeding comparatively

thin stock or glazed stock and toward the left for thicker stock. Adjustably secured adjacent one end of the shaft 122 by means of a set screw 129, is a lever 125 counterpoised by means of a weight 126, the downward movement of which weight is limited by means of a lug 127 projecting from the frame, (Fig. 2).

It will readily be seen that the friction members 64 will normally feed one at a time the sheets advanced by the conveyor 107' in the manner described in my copending application. As the shaft 25 rotates, carrying the crank 101, the pitman 102 and the lever 103 will be reciprocated. So long as the slots 70 are covered with sheets or other articles, this reciprocation will result in lost motion, inasmuch as the disks 59 will ride over the sheets until they have passed the crank 124, and will thus remain out of engagement with the crank. When the disks drop through the slots, the friction pads 64 engage the edge of the foremost sheet and advance it to the feeding rollers. When, however, the slots are uncovered by reason of the fact that sheets or other articles have discontinued being advanced from the table or magazine, the disks 59 will drop through the slots in advance of the crank 124 and will engage the crank, depressing it and thus rotating the shaft 122. This will depress the lever 125 which will engage with the lug 119, thus moving the pawl 106 downwardly, the notch 114 being moved out of engagement with the leaf spring 110.

Tooth 108 of the pawl will thus fall into engagement with the ratchet wheel 109 and the reciprocating motion of the lever 103 will thus be transmitted to the ratchet wheel and thence to the conveyor 107'. This motion is limited by means of the cam 120 which will engage roller 117 of the pawl 106 toward the end of its stroke, lifting it out of engagement with the ratchet teeth. By this means the bringing forward of articles by the conveyor 107 will be limited to the amount desired. Obviously, when the pawl 106 is lifted by the cam, the notch 114 will again engage the leaf spring 110 and the pawl will thus again be retained.

It is also readily apparent that the arcuate member 92 will serve to guide the feed members 64 as they pass around the ratchet wheel 49, restraining their outward centrifugal throw and thus preventing undue jarring and injury of these feed members. By this means, likewise, the feed members are brought gently down on the stock, thus avoiding injury to the sheets which might result from an unrestrained throw of these members onto the stock. Obviously, the counterweight 95 may be adjusted in order that the desired space may be provided between the members 94 and the table. It is also readily apparent that counterpoise 126 will serve to retain the lever 125 out of engagement with the pawl 106.

Having thus described my invention, it is obvious that various immaterial modifications may be made in the same without departing from the spirit of my invention; hence I do not wish to be understood as limiting myself to the exact form, construction, arrangement and combination of parts herein shown and described, or uses mentioned.

What I claim as new and desire to secure by Letters Patent is:

1. In a feeding device, a table for carrying a plurality of articles, non-reciprocating means disposed above the articles and movable relative thereto, article-advancing means mounted on said means and rotatable relative thereto, and means adjacent one end of said non-reciprocating means for limiting the rotary movement of said article-advancing means at this point.

2. In a feeding device, a table for carrying a plurality of articles, sprocket wheels rotatably mounted above said table, a sprocket chain carried thereby, article-advancing members mounted on said sprocket chain and rotatable on an axis parallel to that of said sprocket wheels, and means adjacent one of said sprocket wheels for limiting the centrifugal throw of said advancing members.

3. In a feeding device, a table for carrying a plurality of articles, sprocket wheels rotatably mounted above said table, a sprocket chain carried thereby, article-advancing members mounted on said sprocket chain and rotatable on an axis parallel to that of said sprocket wheels, and an arcuate member adjacent one of said sprocket wheels for limiting the centrifugal throw of said advancing members.

4. In a feeding device, a table for carrying a plurality of articles, sprocket wheels rotatably mounted above said table, a sprocket chain carried thereby, article-advancing members mounted on said sprocket chain and rotatable on an axis parallel to that of said sprocket wheels, an arcuate member adjacent one of said sprocket wheels for limiting the centrifugal throw of said advancing members, the lower portion of said arcuate member being pivotally movable relative to the main portion of said member, and means counterbalancing said pivoted portion.

5. In a feeding device, a table for carrying a plurality of articles, sprocket wheels rotatably mounted above said table, a sprocket chain carried thereby, article-advancing members mounted on said sprocket chain and rotatable on an axis parallel to that of said sprocket wheels, an arcuate member adjacent one of said sprocket wheels for limiting the centrifugal throw of said advancing members, the lower portion of said arcuate member being pivotally movable relative to the main portion of said

member, means adjustably counterbalancing said pivoted portion, and means for limiting the upward movement of said pivoted portion.

6. Sheet feeding mechanism comprising a table for holding sheets, a feeding mechanism including a carriage having a roller and a paper engaging member for advancing sheets one at a time on said table, means for advancing sheets to said feeding mechanism, reciprocating means for actuating said advancing means, means operable by said roller of said feeding mechanism for rendering said reciprocating means effective, and means for limiting the effective movement of said reciprocating means.

7. Sheet feeding mechanism comprising an apertured table for holding sheets, a feeding mechanism for advancing sheets one at a time on said table, means for advancing sheets to said feeding mechanism, means for intermittently actuating said advancing means, a member associated with said feeding mechanism and movable into cooperative relation and compressible within the apertures of said table when in said relation for rendering said intermittent means effective, and means for limiting the effective movement of said intermittent means.

8. Sheet feeding mechanism comprising an apertured table for holding sheets, a feeding mechanism for advancing sheets one at a time on said table, means for advancing sheets to said feeding mechanism, means for intermittently actuating said advancing means, a member associated with said feeding mechanism movable into cooperative relation with the apertures of said table and compressible within the apertures of said table when in said relation for rendering said intermittent means effective, and cam means for limiting the effective movement of said intermittent means.

9. Sheet feeding mechanism comprising an apertured table for holding sheets, a feeding mechanism for advancing sheets one at a time on said table, means for advancing sheets to said feeding mechanism, means for intermittently actuating said advancing means, a reciprocating member for intermittently actuating said advancing means, a pivoted member carried by said reciprocating member and adapted to engage said advancing means for transmitting the motion of said reciprocating member thereto, means for normally maintaining said pivoted member out of engagement with said advancing means, a member associated with said feeding mechanism and compressible within the apertures of said table for causing said pivoted member to operatively engage said advancing means, and cam means for limiting the effective movement of said pivoted member.

10. In a feeding device, a table for carry-

ing a plurality of articles, an endless element located above the table and operable along said table, article advancing means carried by said element and means located at one end of said endless element for presenting said article advancing means to the table.

11. In a feeding device, a table for carrying a plurality of articles, means for conveying an article along the table, said conveying means including an element having means for engaging an article, a track for supporting said element, said track terminating adjacent the table and providing means for presenting the article engaging means to the articles carried by the table.

12. In a feeding device, a table for carrying a plurality of articles, means for conveying an article along the table, and means for advancing an article to the conveying means, said conveying means including an element having means for engaging an article, a track for supporting said element, said track terminating adjacent the table and providing means for presenting the article engaging means to the articles carried by the table, said conveying means providing an element of means for actuating said article advancing means.

13. In a feeding device, a table for carrying a plurality of articles, means for conveying an article along the table, and means for advancing an article to the conveying means, said conveying means including an element having means for engaging an article, a track for supporting said element, said track terminating adjacent the table and providing means for presenting the article engaging means to the articles carried by the table, said conveying means providing an element of means for actuating said article advancing means, and including a yieldable element located adjacent said table.

In testimony whereof, I have hereunto signed my name.

CLAUDE L. POST.
